UNITED STATES PATENT OFFICE

135,461

DESIGN FOR A SPOON OR SIMILAR ARTICLE

Frederick W. Koonz, Bernardston, Mass., assignor
to Rogers, Lunt & Bowlen Company, Green-
field, Mass., a corporation of Massachusetts

Application August 5, 1942, Serial No. 107,819

Term of patent 14 years

To all whom it may concern:

Be it known that I, Frederick W. Koonz, a citizen of the United States residing at Bernardston, in the county of Franklin and State of Massachusetts, have invented a new, original, and ornamental Design for a Spoon or Similar Article, of which the following is a specification, reference being had to the accompanying drawing, forming part thereof.

In the drawing,

Fig. 1 is a plan view of a spoon or similar article showing my new design; and

Fig. 2 is a section taken on line 2—2 of Fig. 1.

The dominant feature of the design resides in the specific configuration and ornamentation of the finial or extreme upper end of the spoon handle as shown in Fig. 1; the ornamentation consisting essentially of the conventionalized representation of three poppy flowers, symmetrically arranged to define the outline of the finial, and the poppies at the sides of the finial displaying the stamens of the flowers.

I claim:

The ornamental design for a spoon or similar article, substantially as shown and described.

FREDERICK W. KOONZ.
